HOUSING FOR AN ELECTRIC CAN OPENER

Robert M. Pinette, Manchester, Conn.

Application October 1, 1958, Serial No. 52,836

Term of patent 14 years

(Cl. D22—2)

Fig. 1 is a top plan view of a housing for an electric can opener showing my new design.

Fig. 2 is a side elevational view, the side opposite thereto being substantially similar in appearance.

Fig. 3 is a front elevational view of said housing.

Fig. 4 is a bottom plan view thereof.

I claim:

The ornamental design for a housing for an electric can opener, substantially as shown and described.
